Watson E. Coleman *Attorney*

UNITED STATES PATENT OFFICE.

GEORGE O. SETTY, OF DINUBA, CALIFORNIA.

MARKER FOR AGRICULTURAL PURPOSES.

1,402,450.

Specification of Letters Patent.

Patented Jan. 3, 1922.

Application filed May 11, 1921. Serial No. 468,509.

To all whom it may concern:

Be it known that I, GEORGE O. SETTY, a citizen of the United States, residing at Dinuba, in the county of Tulare and State 5 of California, have invented certain new and useful Improvements in Markers for Agricultural Purposes, of which the following is a specification, reference being had to the accompanying drawings.

10 This invention relates to a marking device for agricultural purposes and has for its object to provide a device of this character capable of being readily adjusted for various methods of planting.

15 It is also an object of the invention to provide a marker of this character which does not require a special make of wire or cable or the formation of special parts, and wherein the marking buttons may be readily 20 adjusted along the wire or cable to the desired point.

It is another object of the invention to provide a marker of this character embodying marking buttons consisting of a pair of 25 discs adapted to coincide with each other and to receive a portion of a cable therebetween.

It is a further object of the invention to 30 provide a marker of this character wherein the marking buttons may be adjusted along the wire, and clamped without bending or distorting the wire in any manner.

It is a still further object of the invention to 35 provide a marker of this character including marking buttons embodying a pair of discs, said discs having means for the reception of a portion of the cable, and wherein fastening means are disposed on each side of the cable and extended through 40 the discs to firmly clamp the buttons on the wire or cable.

With these and other objects in view the invention consists in the improved construction and arrangement of parts to be herein- 45 after more particularly described, fully claimed and illustrated in the accompanying drawings in which:

Figure 1 is a plan view of a marker constructed in accordance with an embodiment 50 of the invention,

Figure 2 is a sectional view of one of the marking buttons, the cable being also shown in section,

Fig. 3 is a plan view of both sections 55 of the button showing the groove for the reception of the cable, and

Figure 4 is an enlarged side elevation of the structure shown in Figure 1.

Referring to the drawings, 5 designates a length of wire or cable suitable for agricultural marking purposes. This cable may be of any length desired and is adapted to have its end portions formed into loops or eyes. It will be noted that there are no bends, eyes or like parts formed in the cable 60 between the eyes. This is to permit the unobstructed adjustment of the marking buttons 6.

Each of the marking buttons comprise metal discs 7 and 8, the disc 7 having a 70 groove 9 in one face thereof, said groove extending transversely of said face, the groove being substantially segmental in cross section. A plurality of teeth 10 project from the surface of the groove so as 75 to resist movement of the cable through the groove and to permit the disc to bite into the surface of the cable. An opening 11 is provided in the disc 7 on one side of the groove and an opening 12 on the opposite 80 side of the groove, the walls of said openings being smooth, the purpose of which will be hereinafter described.

The disc 8, similar to the disc 7, is provided with a groove 13 which extends transversely of one face of the disc, the groove being substantially segmental in cross section and having a plurality of teeth 14 similar to the teeth 10 of the groove 9. An opening 15 is provided on one side of the 85 groove 13, an opening 16 on the opposite side of the groove, the openings 15 and 16 being threaded and adapted to register with the openings 11 and 12 of the disc 7.

The groove 9 of the disc 7 and the groove 95 13 of the disc 8 are adapted to be disposed in confronting relation so that said grooves cooperate to substantially form a passage for the reception of the cable 5. It will be noted that the diameter of the passage 100 formed by the grooves is considerably less than the diameter of the cable, so as to permit the discs to be firmly engaged with the cable. This is accomplished by means of screws 17, said screws being passed 105 through the smooth openings 11 and 12, and into the threaded openings 15 and 16. By positioning one of the screws on each side of the groove, it is possible to firmly clamp the discs to the cable, as the confronting 110 faces of the discs are not intended for engagement with each other. In view of this,

it is impossible for the marking buttons to move accidentally on the cable, and at the same time, they may be readily moved the desired distance apart by simply loosening 5 the screws 17.

From the foregoing it will be readily seen that this invention provides a novel marker for agricultural purposes, the utility of which is unlimited in view of the adjustability of the buttons. Another important feature is that the discs are compact 10 and substantial, so that they may be used indefinitely with entire satisfaction.

What is claimed is:

15 A marking device for agricultural pur-

poses, comprising a cable, a plurality of marking buttons carried by the cable at spaced intervals, each of said buttons embodying a pair of discs, each disc having a groove in one face thereof, said groove having a plurality of teeth, each of said discs having an opening disposed on each side of the groove thereof, and fastening means extending through the openings of one disc and threaded into the openings of the opposite disc for clamping said discs to the cable. 20 25

In testimony whereof I hereunto affix my signature.

GEORGE O. SETTY.
